ABSTRACT

A dishwashing machine having a hot water rinse compartment through which a train of dish-carrying dollies is moved and a switch actuating comb is mounted in the compartment and has depending tines that are swung in one direction by a dish basket carried by a dolly so as to close a magnetic switch that opens a solenoid valve for spraying rinse water onto the dishes. The comb tines are so mounted that they can freely swing in the opposite direction should it become necessary to reverse the movement of a dolly and its dish basket in the rinse compartment and the magnetic switch will not be closed and neither will the tines be damaged.

**SWINGABLE COMB FOR CLOSING MAGNETIC SWITCH
FOR CONTROLLING HOT RINSE WATER IN A
DISHWASHER**

BACKGROUND OF THE INVENTION

1. Field of the Invention

Some dishwashers have an oval table for supporting a train of dollies on which dish-carrying baskets are removably mounted. These dollies are moved through the dishwasher where the dishes are washed and rinsed. Hot water is used for the rinsing of the dishes and it is necessary to open the hot water valve only when there are dishes in the rinse compartment to be rinsed in order to conserve on the quantity of hot water used. A comb with tines has been used in the rinse compartment and the comb will close a magnetic switch for opening the hot water valve when the comb is swung in one direction by a dish-carrying basket as the dolly moves the basket through the rinse compartment. The tines of the comb are free to be swung in the opposite direction without effecting the closing of the magnetic switch or damaging the tines, should it become necessary to reverse the movement of a dolly for a short distance past the tines for any reason.

2. Description of the Prior Art

A U.S. Pat. No. 2,668,548 was issued on Feb. 9, 1954 to George J. Federighi and Tore H. Noren on a Magnetic Mechanism for Controlling Flow of Rinse Water in a Dishwashing Machine. This patent discloses a dish-carrying basket movable through a dishwashing compartment and one or more dish-rinsing compartments. A mercury switch is mounted outside of the dishwasher and a trip is mounted within the machine and is actuated by a dish-carrying basket and carries a magnet for controlling the opening and closing of the switch. When the trip is in normal position, a magnet is disposed close to the mercury switch for holding the switch open. An electrically operated rinse water valve is connected to the switch and remains closed so long as the switch remains open.

It is vital that the final rinse water be turned on only when the dishes are in a position to be given a final rinse in order to save on the quantity of hot water used. The dish basket will actuate the trip for closing the switch that opens the hot water valve so that the dishes can be rinsed.

Another U.S. Pat. No. 2,864,387 was issued on Dec. 16, 1958 to the same two above-mentioned patentees and it pertains to a Dishwashing Machine with Automatic Final Rinse Control. An endless conveyor is disclosed in this patent for conveying dishes through the dishwasher rather than using dollies for supporting dish-carrying baskets. A comb with tines is placed in the rinse compartment and any dishes being carried by the upper reach of the endless conveyor will strike one or more tines and swing the comb in one direction for causing the latter to close a mercury switch and open a valve controlling the flow of hot water into the rinse compartment. No mechanism is shown in this patent for permitting the tines to swing in the opposite direction because there was no need for this since the upper reach of the endless dish-carrying conveyor travelled in only one direction for conveying the dishes through the dishwasher including the rinse compartment.

SUMMARY OF THE INVENTION

An object of my invention is to provide a comb in the rinsing compartment of a dishwasher that will be swung in one direction for opening the valve for the hot water when the comb tines are contacted by a dish-carrying basket as it is moved by its supporting dolly through the rinse compartment. A train of dollies is mounted for movement along an oval table that will successively move the dollies one at a time into the dishwasher and through the rinse compartment. The tines are so mounted on the comb that they are free to swing in an opposite direction should it become necessary to move the dollies and dish-carrying baskets in a reverse direction through the rinse compartment. Each tine is removably secured to the comb and it may be readily replaced by a new tine in case it becomes damaged.

BRIEF DESCRIPTION OF THE DRAWINGS

FIG. 1 is a top plan view of an oval table adapted to feed a train of dish-carrying dollies through a dishwashing machine. 5 The train of dollies and the endless track for supporting the dollies are not shown in this figure.

FIG. 2 is an enlarged transverse section through the final 10 rinse compartment of the dishwasher and is taken substantially along the line 2-2 of FIG. 1. A comb is illustrated in this figure as having tines that lie in the path of the moving dish-carrying baskets so as to be actuated thereby for swinging the comb to close an electric switch that will open the rinse water valve for rinsing the dishes. A dolly and a dish-carrying basket are shown in this figure.

15 FIG. 3 is a longitudinal section through the final rinse compartment of the dishwasher and is taken substantially along the line 3-3 of FIG. 2.

FIG. 4 is an enlarged transverse section through a portion of the comb that controls the opening of the hot water valve for 20 the final rinsing of the dishes. It is taken along the line 4-4 of FIG. 2 when looking from the right hand side of the figure. This is looking from the opposite direction to that of FIG. 3 where one is looking from the left hand side of FIG. 2.

DESCRIPTION OF THE PREFERRED EMBODIMENT

In carrying out my invention I make use of a dishwashing machine that is schematically shown in a top plan view in FIG. 1, and it includes a power wash compartment A, a power rinse compartment B and a final rinse compartment C. I do not wish 30 to be confined to any particular type of dishwasher and it is not vital to the invention that the dishwasher be provided with both a power rinse and a final rinse compartment. All that is necessary is that my invention be placed to control the flow of hot water in the final rinse so that the hot rinse water is turned on only when there are dishes in the compartment to be rinsed.

An oval table D is associated with the dishwasher and it is 40 preferably made in sections as shown in FIG. 1, of the type shown in my U.S. Pat. No. 3,447,491, issued June 3, 1969, entitled Sectional Oval-Shaped Table for Endless Conveyor for Dishwasher; and in my U.S. Pat. No. 3,511,192, issued May 12, 1970, on a Sectional Oval-Shaped Table with Side Walls and U-Shaped Tongues Interconnecting Adjacent Sections. 45 The sectional oval table D is provided with an endless pair of dolly guiding rails, not shown in FIG. 1, but shown in transverse cross section at E and F in FIG. 2. In the enlarged longitudinal section through the final rinse compartment C, see FIG. 3, I show one of the dolly guide rails F. Each guide rail is 50 provided with a longitudinally extending groove in which dolly-supporting wheels 1 and 2 ride. These wheels support a dolly, shown by dot-dash lines at G in FIG. 2, and the dolly carries a dish-retaining basket H, also indicated by dot-dash lines. The particular type of dolly that is preferably used is 55 shown in my U.S. Pat. No. 3,550,755, issued Dec. 29, 1970, on an Endless Conveyor for a Dishwasher with Links Interconnecting Adjacent Dollies. I do not wish, however, to be confined to any particular type of dolly or dish-carrying basket. Any means may be used for moving the basket H through the 60 final rinse compartment C and my invention pertains to a novel type of comb that will be contacted and swung by the moving basket and the swinging of the comb will close the electric switch which will open the hot water valve and direct rinse water against the dishes for rinsing them.

65 In FIGS. 2 and 3, I show a comb, indicated generally at J, as being mounted in the final rinse compartment C of the dishwasher. The comb consists of a number of tines 3, see also FIG. 4, that are mounted in tubular supports 4. The latter are welded or otherwise secured to sleeves 5 which in turn are 70 rotatably mounted in abutting relation on a transversely extending shaft 6. The ends of the shaft 6 are received in bearings 7 which in turn are secured to the side walls 8 of the final rinse compartment C. Each tine 3 has its upper end projecting above its tubular support 4 and a cotter pin 9 is inserted through an opening in the tine and it rests on the top of

the support for removably supporting the tine. The lower portion of the tine that is contacted by the basket H may be provided with a plastic or rubber sleeve 10 that will protect the tine. If any tine becomes damaged it is a simple matter to remove its cotter pin 9 and slip the tine out of its tubular support 4 and then substitute a new tine for the damaged one.

I will now describe how the swinging of the tines 3 by a moving basket H will actuate a mechanism for closing a switch that will open a hot water valve. Both FIGS. 2 and 4 show the shaft 6 provided with a pair of arms K that are keyed to the shaft so that a swinging of the arms will rock the shaft. A transversely extending bar L is connected to the two arms K by threaded shanks 11 that extend through the bar and have their other ends connected to the arms. It is possible to adjust the bar L toward or away from the arms K by adjusting the nuts 12 and 13 on the threaded shanks 11, these nuts being placed on opposite sides of the bar as is clearly shown in FIG. 4. A lock nut 14, also mounted on each threaded shank 11, aids in securing the shanks to the arms K. The bar L can be adjusted on the threaded shanks 11 so that the weight of the bar will counterbalance the weight of the tines 3 and sleeves 4.

It will be noted from FIG. 4 that the arms K, threaded shanks 11 and bar L extend off at an angle from the axis of the shaft 6 instead of depending vertically in a downward direction from the shaft. This is due to the fact that the weight of the arms K, threaded shanks 11 and bar L is counterbalanced not only by the tines 3 and sleeves 4, but also by an arm M that is keyed to the shaft 6 and extends vertically above the shaft and carries a threaded horizontal shank 15 that projects to the opposite side of the shaft from that of the bar L. A magnet holding casing N is mounted at the outer end of the shank 15 and it contains a horse shoe magnet, shown by dotted lines P in FIG. 2. The casing N is held in adjusted position on the shank 15 by nuts 16 and 17 and a lock nut 18 secures the shank in the arm M, see FIG. 4.

It is important that the magnet holding casing N and the magnet P be positioned near to the top wall 19 of the final rinse compartment C when the magnet is in normal position, see FIG. 3. The reason for this is so that the magnet can act on a magnetizable arm 20 of an electric switch Q to hold this arm out of contact with the other stationary arm 21 of the switch and thus normally hold the switch in open position. The bar L can be adjusted on the threaded shanks 11 so as to cause the bar to be disposed to the left of the shaft 6, as shown in FIG. 3, and the magnet P will be disposed to the right of the shaft and positioned under the switch Q to maintain it in open position. When the bar L is in this position and if there is no basket H of dishes moving through the final rinse compartment C, the tines 3 will hang straight down and will lie in a vertical plane as shown by the full line position of the tines.

In FIG. 3, I show a dolly G with a dish-containing basket H moving from the right to the left. The basket H will strike the tines 3 of the comb J and swing them in a clockwise direction about the shaft 6 as a center. The sleeves 5 will freely rotate on the shaft 6 as the tines 3 are swung by the basket H, contacting therewith. The swinging tines will have no effect on moving the transverse bar L until they actually strike the bar as is clearly shown by dot-dash lines in FIG. 3. When this takes place, the bar L will be swung from its full to its dot-dash line position and the magnet P and its housing N will be moved away from the electric switch Q. The magnetizable switch arm 20 will be freed from its magnetic attraction to the magnet P and it will swing to contact with the stationary switch arm 21 and close an electric circuit to open a solenoid controlled valve R, see FIG. 3. A main switch 22' has already been closed which will connect the solenoid valve R to a current source, not shown, when the switch Q is closed.

Again referring to FIGS. 2 and 3, it will be seen that the hot water pipe S leads to a spray head T in the final rinse compartment, and this spray head has outlet spray nozzles 22. Dot-dash lines 23 indicate how the hot rinse water will be sprayed onto the dishes only when a basket H of dishes is actually moving through the rinse compartment. As soon as the dish basket

H clears the tines 3 of the comb J, the tines will swing back into a vertical depending position and will force the bar L so that its weight will swing it from the dot-dash line position of FIG. 3 back into the full line position in the same figure. This will swing the magnet P and its housing N in a counter-clockwise direction from the dot-dash to the full line position. The magnet P will again attract the magnetizable arm 20 of the switch Q to open it and permit the spring-biased solenoid valve R to close and stop any further flow of hot rinse water from the spray head T.

One important feature of the invention is the free swinging of the tines 3 in a counter-clockwise direction when looking at FIG. 3, should it become necessary to move the dolly G and basket H in a reverse direction, i.e. from the left to the right in this Figure. The tines 3 will not be damaged through such swinging movement and they will not contact with the bar L during such a counter-clockwise movement. FIG. 3 shows by dot-dash lines how the tines 3 of the comb J are free to swing to the right from the full line position should it become necessary to reverse the direction of movement of the dolly G and basket H, which will cause the right hand edge of the basket to contact and swing the tines. In this manner the tines 3 will not be damaged nor will the shank 15 and the magnet P be moved when it becomes necessary to move the basket H in a reverse direction for any reason.

I claim:

1. In a device having supporting means including bearings:
  - a horizontal shaft rockably supported in said bearings;
  - a plurality of sleeves mounted to freely rotate on said shaft;
  - a substantially vertical tubular support connected to each sleeve;
  - a tine removably secured in each tubular support and depending in a substantially vertical position;
  - a pair of arms keyed to said shaft so that a swinging of the arms will rock the shaft;
  - a bar paralleling said shaft;
  - means for adjustably connecting said bar to said arms so that a swinging of the bar about the axis of said shaft will rock the shaft;
  - a shank extending from said shaft and being swingable in an arc when the shaft is rocked;
  - a magnet supported at the outer end of said shank;
  - the means connecting said bar to said arms being adjustable for positioning the bar the desired distance from said shaft for holding said shank in the desired angular position and for spacing said bar from the normal depending position of said tines, said bar counterbalancing the weight of said shank and magnet;
  - whereby a swinging of one or more times in one direction about said shaft and toward said bar will strike the bar and swing it for rocking the shaft and moving said magnet away from its normal position, said tines being free to swing in an opposite direction and away from said bar without effecting any movement of said shaft, shank and magnet.
2. The combination as set forth in claim 1: and in which
  - each tine has its upper end projecting a short distance above the top of its tubular support; and
  - a cotter pin is removably disposed in a transverse opening near the top of the tine and rests on top of the tubular support for removably connecting the tine to its support.
3. The combination as set forth in claim 1: and in which
  - the means for adjustably connecting said bar to said arms includes a threaded shank connected to each arm and extending radially from said shaft;
  - said bar having openings through which said threaded shanks extend; and
  - nuts mounted on said threaded shanks and being adjustable for positioning said bar the desired distance from said shaft.
4. The combination as set forth in claim 1: and in which

- a. the sleeves on said shaft abut each other and the arms that are keyed to the shaft, abut the opposite ends of the row of sleeves for holding them and said tines from any movement with respect to the length of the shaft.
